UNITED STATES PATENT OFFICE.

JOHN J. MILLER, OF CHICAGO, ILLINOIS.

PLASTERING MACHINE.

Application filed September 5, 1923. Serial No. 661,055.

To all whom it may concern:

Be it known that I, JOHN J. MILLER, a citizen of the United States, residing at 600 West Erie St., Chicago, in the county of Cook and State of Illinois, have invented certain new and useful Improvements in Plastering Machines; and I do hereby declare the following to be a full, clear, and exact description of the invention, such as will enable others skilled in the art to which it appertains to make and use the same.

This invention relates to a novel plastering machine adapted to convey plaster from a suitable receptacle or hopper and to discharge the same onto a spreader or revoluble trowel to facilitate the plastering of walls and the like and greatly reduce the cost and amount of work and energy required, over any method now or heretofore practiced.

Another object of the invention is to provide a novel plastering machine by which the plaster or other cementitious material is forced through a conduit by motive power, to the spreader or trowel so that the receptacle for containing the plaster may be positioned on the ground or floor and conveniently filled with the prepared or mixed cementitious material in a desirable and economical manner obviating the necessity of manually handling and transporting the plaster to convenient positions around the ceiling or walls of a room or the like.

Still another object of the invention is to provide a novel form of trowel or spreader adapted to be revolved from a motor which also constitutes motive power for driving a force-pump or conveyor to raise the material to the point of application, means being provided to control the flow of the materials to cut off the same or regulate the volume thereof, while novel means are also provided to control the operation of the driving means for lifting the material or revolving the trowel so that they may be operated together or simultaneously or the trowel operated independently by the operator handling the appliance, the trowel being also mounted to move at various angles and a nozzle being provided at the outlet end of the conduit to spread the material over the entire surface or any portion of the trowel to facilitate the application thereof and insure uniformity of thickness.

The invention in a preferred form is il-

lustrated in the drawings and hereinafter more fully described:

Figure 1 is an elevation of my novel plastering machine, also showing the wiring arrangement for controlling the operation of an electric motor used for driving purposes.

Figure 2 is an enlarged sectional elevation showing the revolving trowel and adjacent parts, the same being taken on the line 2-2 of Figure 3.

Figure 3 is a rear elevation of the parts shown in Figure 2.

Referring to the drawings in detail, in which like reference characters designate corresponding parts throughout the several views, 4 indicates a receptacle or hopper in which plaster or other cementitious material 5, which has been previously mixed, is placed. The hopper is preferably funnel-shaped and discharges into a conveyor or force-pump 6 which is adapted to be driven by a prime mover shown in the form of an electric motor 7, all mounted upon a suitable base 8 adapted to be arranged upon the floor. A clutch 9 is designed to connect the drive shaft of the motor with the pump 6 and is adapted to be thrown into and out of engagement and controlled electrically or otherwise to drive the pump at will or stop it as desired.

One end of the motor shaft is adapted to be connected to the pump and the other end has connected thereto through the medium of a coupling 10, a flexible shaft 11, the length of which may be adjusted or varied as desired. This shaft leads along an elongated tubular handle 12 upon the opposite end of which a revolving trowel or spreader 13 is rotatably mounted at right angles to its surfaces. This trowel is preferably in the form of a circular plate or disk, of metal or other material, having its edge 14 angularly extended away from its face, but may be of any other suitable form desired. The axis upon which the plate is mounted to rotate, is designated at 15, and is pivoted, swiveled, or otherwise mounted for angular or any other movement and adjustment with respect to the handle 12 as indicated at 16, so that the trowel may be positioned in any desired angular relation to the handle for operating on surfaces extending vertically, horizontally, or otherwise, with convenience.

For driving the plate 13, suitable connec-

tion may be made directly or indirectly with the flexible shaft 11, but as shown, a gear 17 is fixed to the back of the plate, as indicated at 18, and mounted to rotate on the axis 15, which may be headed as indicated at 19 to prevent displacement of the hub of the gear. A bearing 20 is fixed on the axis or axle 15 and has an arm 21 in which a shaft 22 is journaled, the shaft being in turn coupled or rigidly connected to the adjacent end of the flexible shaft 11, as indicated at 23, at one end, and having fixed on its opposite end a smaller beveled gear or pinion 24 disposed in mesh with the beveled gear 17 whereby the speed of rotation of the trowel or plate thereof may be reduced or regulated as desired, according to the speed of the motor or suitable reduction gear interposed therebetween.

20 A conduit 25 leads from the outlet of the conveyor or pump 6 and is provided with a valve 26, if desired, to cut off or control the discharge of material from the conveyor or pump and the forcing thereof, under pressure, fluid or otherwise, through the conduit or pipe 25. The pipe 25 is preferably flexible and adapted to withstand considerable pressure, being also adjustable or variable in length to correspond with the flexible shaft 11 so that all points within a room may be reached. The conduit 25 extends along the handle 12 and there, may be clamped or fastened thereto, as indicated at 27, together with the flexible shaft 11, as shown in Figure 2 of the drawings. The bearing 20 is provided with a plate extension 28 preferably sector-shaped and extending at an angle toward the plate 13 as more clearly shown in Figure 2 of the drawings, with the peripheral edge thereof located beyond the periphery of the plate and formed with a double-walled nozzle 29 the discharge opening 30 of which preferably turns inwardly towards the edge of the plate to discharge the material 5 adjacent or onto the same, as also seen in Figure 2. The nozzle 29 is provided with a central sleeve 32 to which the adjacent or discharge end of the conduit 25 is coupled as indicated at 33, so that when the conveyor or pump is operating, driven by the motor, the material will be conveyed through the conduit and discharged from the nozzle onto the plate, there to be applied by pressure and by the rotation of the plate as the operator, while grasping the handle 12, moves the trowel over the surface to be covered, thereby effectively spreading the plaster, or the like, upon the surface of the wall and at the same time smoothing it out.

As means for controlling the operation of the motor to drive the plate or disk 13 of the revolving trowel or spreader, or to stop the same, as desired, and also to control the clutch 9, that is, to throw it in and out for

connecting the conveyor or pump 6 with the motor 7, whereby material will be conveyed or not, and to permit independent operation of the trowel as well as simultaneous operation of the trowel and the feeding of the material, a novel arrangement is provided. This control is preferably effected electrically, and as shown, a switch 34 is provided upon the handle 12 and has wires 35 and 36 leading therefrom and connected to the motor 7 to control the operation thereof from a suitable source of electrical energy, not shown. The switch 34 may be of any suitable type, such as the usual button switch. A corresponding switch 37 is provided on the handle and connected by conductors or wires 38 and 39 to an electromagnet such as designated at 40 in diagrammatic form, or other suitable means for controlling the operation of the clutch 9 whereby it may be conveniently thrown in and out for connecting or disconnecting the conveyor or pump 6 with respect to the motor 7.

In the operation of the device, the plastic material is deposited in the hopper 4 for discharge into the conveyor or pump 6, which may be of any suitable construction. The supply of plaster or other suitable cementitious material to be spread upon a surface or otherwise applied, may be maintained or replenished, by the same operator or an additional workman. The operator then grasps the handle 12 and by manipulating the switches 34 and 37, may start the motor to drive the shaft 11 and through the operative connections thereof with the plate 13 of the revolving trowel, rotate the latter. By operating the clutch 9, the conveyor or pump 6 may be connected to the motor to force the material under fluid or air pressure or otherwise, through the conduit 25 for discharge through the nozzle 29 slightly in advance of, and upon the plate 13. By applying the proper pressure to the plate by means of the handle, the material will be effectively applied, spread, and caused to adhere to the surface to be coated or covered. The volume of material flowing may be regulated by the valve 26, and if desired, the conveyor may be disconnected from the pump simply by pressing a button or operating the switch 37, so that the trowel may be driven without feeding the material, so that the surface may be effectively smoothed, or finished. That is, the material may be fed while the trowel is revolving, this being of use when applying a first coat. Ordinarily, however, the trowel will be driven when applying a second coat, as well as in applying the first coat.

Thus it will be seen that plastering operations may be quickly, effectively and conveniently as well as economically carried on by means of a plastering machine con-

structed in accordance with my invention. It eliminates useless handling of material and one operator can plaster or coat a larger surface area in a given length of time, than 5 several operators, in accordance with the present system. By providing the handle 12 of the proper length, derricks or scaffolding need not be employed, unless the walls and ceiling are extraordinarily high. The device 10 may be conveniently controlled and by it, any desired degree of pressure may be applied, according to the material used, and while, as shown, a form which I now consider a preferred embodiment of the invention 15 is illustrated, it is to be understood that I do not desire to be restricted in this respect, as the drive connections between the shaft and the trowel plate, and the details of construction, form and arrangement of 20 the other parts, may be varied as desired so long as they do not depart from the spirit and scope of the invention as hereinafter claimed.

Having thus described my invention, what 25 I claim is,

1. In a plastering machine, a supporting member having a bearing, said bearing being adjustable angularly with respect to the support, a trowel rotatably mounted in 30 the bearings, and a discharge nozzle adjacent the trowel and having connections with a source of supply for plaster.

2. In a plastering machine, a handle, a bearing on the handle, a trowel rotatably 35 mounted on the bearing and adjustable angularly with respect to the handle, driving means for the trowel, an elongated discharge nozzle adjacent the trowel and adapted to spread the material thereon, means for 40 forcing the material through the nozzle, and means controlling the driving means and forcing means.

3. In a plastering machine, a revolving trowel, a nozzle having an arcuate discharge 45 orifice extending around and adjacent to the edge portion of the trowel, a motor having operative connections with the trowel for driving the same, a hopper, a pump for receiving plaster from the hopper and forcing 50 the same therefrom, a conduit for conveying the discharged plaster from the pump to the nozzle for discharge upon the trowel, operative connections between the motor and pump, and means in proximity to the trowel 55 for causing the operation or inoperation of the motor and pump.

4. In a plastering machine, a handle, a

spindle pivoted on the handle, a trowel mounted on the spindle, and means for supplying plaster to the trowel.

5. In a plastering machine, a handle, a trowel mounted on the handle, a motor, driving connections between the motor and the trowel for rotating the latter, means for angularly adjusting the trowel with respect 65 to the handle, a pump for forcing material onto the trowel, and means on the handle for controlling the operation of the motor.

6. In a plastering machine, a handle, a trowel mounted on the handle, a motor, 70 driving connections between the motor and the trowel for rotating the latter, a pump for forcing material onto the trowel, means for connecting the pump to the motor or disconnecting the same, and means on the 75 handle for controlling the motor, and the latter means, and means upon the handle to electrically control the operation of the motor and connecting means between the motor and the pump to permit independent 80 operation of the trowel or simultaneous operation of the trowel and pump.

7. In a plastering machine, a handle, a spindle pivoted to the end of the handle, a bracket mounted on the spindle, a discharge 85 nozzle carried by the bracket, a trowel rotatably mounted on the spindle and means supported from the spindle for rotating the trowel.

8. In a plastering machine, a handle, a 90 spindle pivoted to the end of the handle, a bracket mounted on the spindle, a discharge nozzle carried by the bracket, a gear mounted on the bracket, a trowel rotatably mounted on the spindle and a gear carried by the 95 trowel adapted to mesh the gear mounted on the bracket.

9. In a plastering machine a rotary disk trowel and means for supplying and directing the plaster inwardly to the trowel adjacent its periphery.

10. In a plastering machine a rotary disk trowel having a peripheral lip and means for supplying and directing plaster inwardly from adjacent its periphery under 105 said lip.

11. In a plastering machine a rotary disk trowel in combination with a plaster conveying nozzle having an arcuate discharge mouth positioned beyond but adjacent the 110 periphery of the trowel and directed inwardly toward the trowel's axis of rotation.

In testimony whereof I affix my signature.
JOHN J. MILLER.
